CLAIM

The ornamental design for a vehicle bumper protector, as shown and described.

DESCRIPTION

FIG. 1 is a front, top, and left side perspective view of the vehicle bumper protector embodying my new design; FIG. 2 is rear, bottom, and left side perspective view thereof; FIG. 3 is a top plan view thereof; FIG. 4 is a bottom plan view thereof; FIG. 5 is a left side elevation view thereof; FIG. 6 is a right side elevation view thereof; FIG. 7 is a rear elevation view thereof; FIG. 8 is a front elevation view thereof; and, FIG. 9 is a perspective view thereof, showing the vehicle bumper protector in use. The broken line showing of a vehicle is provided for the purpose of illustrating environmental structure and form no part of the claimed design.
